COMBINED POST AND BRACKET

William J. Horgan, Jr., 1299 Folkstone Drive,
Pittsburgh, Pa. 15243

Original design application July 2, 1969, Ser. No. 18,032.
Divided and this application Oct. 13, 1970, Ser. No.
25,471

Term of patent 14 years

Int. Cl. D25—01

U.S. Cl. D13—7

FIG. 1 is a perspective view taken from the left of a combined post and bracket embodying my new design;

FIG. 2 is a right side view of a combined post and bracket shown in FIG. 1;

FIG. 3 is a front view of a combined post and bracket shown in FIG. 1;

FIG. 4 is a back view of a combined post and bracket shown in FIG. 1;

FIG. 5 is a bottom view taken as indicated by the lines and arrows 5—5 in FIG. 4;

FIG. 6 is a top view taken as indicated by the lines and arrows 6—6 in FIG. 4;

This is a division of application Ser. No. D. 18,032, filed July 2, 1969, now Design Patent D. 220,476.

I claim:

The ornamental design for a combined post and bracket, as shown and described.
